Term of patent 14 years

Int. Cl. D6—99

U.S. Cl. D33—3

FIG. 1 is a perspective view of my design having a rail member and two clamping members slidably received thereon;

FIG. 2 is a partial front elevational view of FIG. 1 showing one of the clamping members and a portion of the rail member;

FIG. 3 is an end view of FIG. 1 taken from the right end thereof;

FIG. 4 is a plan view of FIG. 2;

FIG. 5 is a bottom view of FIG. 2;

FIG. 6 is an enlarged perspective view showing one of the two clamp members in greater detail;

FIG. 7 is a perspective view taken from the rear and bottom of the clamping member of FIG. 6.

I claim:

The ornamental design for a support rack for medical implements, substantially as shown and described.
